UNITED STATES PATENT OFFICE

HORATIO S. LYNESS, OF LYNN, MASSACHUSETTS, ASSIGNOR TO UNITED SHOE MANUFACTURING CORPORATION, OF PATERSON, NEW JERSEY, A CORPORATION OF NEW JERSEY

PERFORATING MACHINE

Application filed July 13, 1928. Serial No. 292,406.

This invention relates to perforating machines, and particularly to those of the die-cutting type used for perforating or punching the upper leather parts of boots and 5 shoes.

Machines of the type to which this invention relates employ interchangeable gang or pattern dies provided with cutting edges arranged according to the pattern of the 10 perforations or cut-outs which it is desired to form in the shoe part. In such machines, the work is interposed between the die and a co-operating presser member so that at a single 15 operation of the machine the cutting of a plurality of perforations corresponding to the whole pattern of the die is effected. On account of the heavy cutting pressure required between the die and the presser member in order to effect a clean-cut severance of 20 the cut-out pieces of leather, perforating machines of this class are usually designed with a frame having heavy lateral tie members. On this account, limited clearance is allowed for the die between them and it is 25 the practice to mount the die so that it may be brought forwardly out of range of the presser member to allow the operator to position the work accurately over the die while it is in plain view. The die and the super- 30 posed work piece are then pushed back into the frame of the machine within the range of the presser member.

Various hold-down members have been 35 designed with a view to positioning the work piece with reference to the die and holding it in position while it is being presented in cutting position. In one of its aspects, the present invention consists in a die having an improved hold-down device for use in connection with a perforating machine of this 40 type, while in another aspect it consists in an organization of perforating machine parts, including a movable die holder, die and stripper plate combined in novel fashion with a hold-down element.

In still another aspect, the invention consists broadly in a die having a reversible hold-down device whereby a shoe part may be presented either side up in cutting position. The character of the cut-out or perforation.

ration desired in shoe parts is usually non-symmetrical and must, therefore, be reversed in the right and left parts. Inasmuch as it is not practical to locate a shoe part by reference to its lined side, it has 55 been the practice to provide right and left dies or die gangs and to set the machine up for right and left shoe parts by using these dies respectively. Where the cut-out is extensive or intricate in its design, the expense 60 of right and left-hand dies is a considerable item. There is, moreover, considerable loss of time in removing and replacing the right and left dies and the problem of storage 65 space for two dies of each pattern used by 70 the manufacturer.

With these considerations in view, an object of the invention is to provide a reversible hold-down wherein a shoe part may be located always from its finished surface and then presented to a non-symmetrical die either side up in cutting position. To this end, an important feature of the invention consists in a hold-down comprising super- 75 posed holding members each having a work-opening for the die and an associated position-locating device or gauge whereby a right or left shoe part may be located by reference to its finished side.

A further feature of the invention consists 80 in means for detachably retaining the hold-down in position upon a die holder which will permit the hold-down to be removed and disposed either side up to receive the shoe part, according as it is a right or a left part. Having positioned the shoe part, gauging it from its finished face in respect to one plate if it is a right part and in respect to the other plate if it is a left plate, the hold-down is replaced as a unit with the work 85 piece either side up, as the case may be. The hold-down preferably comprises a pair of superposed holding members having one element of a hinge connection, while the die holder is provided with the other element 90 of the hinge connection. The shoe part may be located in the hold-down while the latter is connected to the die holder and by reference to the finished side of the part, or the hold-down may be detached and reversed to 95 100

receive the shoe part and then turned back to its initial position and replaced above the die.

These and other features of the invention will be best understood and appreciated from the following description of a preferred embodiment thereof, selected for purposes of illustration and shown in the accompanying drawings, in which

10 Fig. 1 is a view in perspective of a die holder equipped with the reversible hold-down;

Fig. 2 is a plan view of the same;

15 Fig. 3 is a view in side elevation with parts broken away;

Figs. 4 and 5 are views in perspective, on a smaller scale, showing the hold-down in two positions; and

20 Fig. 6 is a view in perspective of a shoe part which has been perforated by the die shown in the drawings.

The die holder and die herein shown may be used in a perforating machine of any well-known commercial type such, for example, as that fully disclosed in U. S. Letters Patent No. 1,439,019, granted December 19, 1922 upon an application of C. W. Newton, to which reference may be had for details of the machine construction.

25 30 The die holder comprises a rectangular plate 10 adapted to be secured by a screw stud 11 to a sliding carrier supported on the bed of the machine and to be moved in and out thereon for placing the work in position and presenting it to the machine. A die block 12 is rigidly secured to the plate 10 and carries the individual dies 14 of the gang or pattern. The individual dies are arranged with their cutting edge uppermost and register with openings in the die block which permit the passage of the cut-out pieces of the work. As herein shown, the pattern comprises a number of elongated and square individual dies arranged non-symmetrically

35 40 45 and constituting a multiple die for producing in the vamp of a shoe the design shown in Fig. 6. This, it will be observed, is not symmetrical so that it must be reversed in right and left parts.

50 55 60 Associated with the die gang is a stripper plate 16 having downwardly extending posts 18 which slide in sockets in the plate 10 and being normally maintained in a position slightly above the cutting edges of the die gang by compression springs which encircle the posts 18. The stripper plate 16 has a cut-out opening shaped to surround the die gang so that when the stripper plate is depressed in the dieing-out operation the work piece is brought into contact with the cutting edges of the die. All of the construction above described may be of any commercial or well-known construction.

65 The hold-down device comprises a pair of plates or leaves 30 and 32, corresponding in

their general outline to the shape of the die carrier 10 and hinged together at their forward end by being riveted to the sides of spring plates 37 which are folded so as to form a hinge 36 and act to maintain the plates 30 and 32 separated, so that the operator may conveniently present a work piece between them. The hinges 36 are each extended outwardly in the form of a stud or sleeve and act as one member of a hinge for the hold-down in its entirety. The outstanding portions of the hinge 36 are received in curved slots formed by hook-shaped members 20 secured rigidly to the sides of the die carrier 10 and extending beyond its front end. A leaf spring 22 is secured to the surface of the die carrier adjacent to each of the hook members 20 and arranged so as to underlie the hinge 36 and hold it normally in position at the end of the slot in the hook members 20. The arrangement is such that the hold-down may be detached from the die carrier by pulling it rearwardly so that the springs 22 are forced down and the hinge members 36 allowed to pass out under the end of the hook. Similarly, the hold-down may be replaced by positioning the hinge members opposite the ends of the hooks and pushing it forwardly.

70 75 80 85 90 95 100 105 110 115 120 125 The hold-down plate 32 is provided with an opening 38 of the same general shape as that in the stripper plate 16 but has position locating devices comprising at its rear edge the gauge points 45 and at its right side a gauge finger 40. The plate 30 is provided with a similar opening and has a similar gauging finger 41. These openings register and expose the portion of the work in which the perforated design is to be formed. Both of the plates are extended at the rear of the work-openings sufficiently to enable the operator to handle them conveniently and to close the plates together upon the work piece and hold them in this condition during the dieing-out operation. Both of the plates are provided with slots 35 near one corner which register with a pin 34 projecting from the die carrier and so positively locate the hold-down in proper position when it is depressed. The pin 34 and slots 35 determine positively and accurately the transverse position of the hold-down at its rear or outer end. At its forward end, the plates 30 and 32 are notched to fit between the side surfaces of the hook members 20 so that the hold-down is positively positioned by them at its other end.

The plates 30 and 32 of the hold-down are provided with co-acting curved portions 33 between which the work is engaged in a bent condition so that the gripping action of the plates is intensified and the work held securely against displacement.

In using the hold-down of my invention in perforating vamps, such as that shown in

Fig. 6, the vamp is positioned between the plates of the hold-down with its finished side 15 up and by reference to the gauge points of the plate which is uppermost. Such a condition is shown in Fig. 4, where it will be seen that the recess between the two buttonhole tongues is located with respect to the gauge finger 40 and the upper edge of the vamp with respect to the gauge fingers 45.

10 The vamp may be located freely and accurately while the plates of the hold-down are held lightly together by the operator, either while the hold-down occupies the position shown in Fig. 1 or when it has been removed 15 from the die holder and placed upon the bench. The hold-down plates are then pressed together, flattening the work to be perforated and holding it in gauged position. The hold-down being in position, and 20 interlocked with the die carrier is pushed into operative position and the perforating operation takes place.

In dealing with a left vamp which must be presented to the die with the lined side 17 uppermost, the hold-down is detached from the die holder and reversed, as suggested in Fig. 5, and the vamp located with respect to the gauge points 45 of the plate 30 instead of 32. When the vamp has been positioned 30 or interleaved as already explained, the hold-down is reversed in its entirety together with the work piece and returned to position upon the die carrier with the same side of the hold-down up as before but with the vamp reversed. In the dieing-out operation which ensues, a pattern in reversed position is produced in the shoe part.

It will be apparent that the operation of locating the vamp in the latter case is performed as before except for its reversal in position, that is to say, the vamp is located from its finished side with reference to the gauge finger 41 which is now disposed at the left side of the hold-down instead of the gauge finger 40 which in the preceding operation, with the hold-down reversed, was located at the right side of the hold-down.

While I prefer to shape the two plates of the hold-down similarly, it is not important 50 to do so as it is essential only to provide members which will retain the shoe part in position and afford gauging means of some kind.

Having thus described my invention, what I claim as new and desire to secure by Letters Patent is:

1. In combination, a die having a base, and a reversible hold-down having a readily detachable connection with said base, comprising readily removable, reversible, superposed holding members each having a work opening and an adjacent position-locating device, whereby a shoe part may be located by reference to its finished side between said holding members and presented either side 60 up in cutting position.

2. In combination, a die, and a reversible hold-down detachably connected thereto, comprising a pair of jointly removable, interconnected superposed sheet metal members having similarly disposed non-symmetrical openings therein in respect to which a shoe part may be located by reference to its finished side and then presented in cutting position, held between said members and either side up according as the part is a right or 75 left part.

3. In combination, a die having a holder, and a detachable hold-down interlocked therewith, said hold-down comprising superposed coextensive holding members each having a work opening and an adjacent locating device, whereby a shoe part may be positioned by reference to its finished side with respect to one holding member or the other, and means for interconnecting the holding 80 members shaped to constitute one element of the interlocking connection with the die holder.

4. In combination, a die, and a detachable hold-down for said die, comprising hinged holding plates for an interposed shoe part and having work-openings of identical size and shape therein, a gauge device associated with one plate for locating a right shoe part, a gauge device associated with the other plate for locating a left shoe part, and means for accurately locating the hold-down as a unit with respect to said die with the shoe part contained therein.

5. In a perforating machine, a die holder, a multiple die carried thereby, a hold-down comprising connected holding plates between which a shoe part may be placed either side up and having registering openings for the die, and means for retaining the hold-down 100 in position upon the die holder with either the finished face or the lined face of the shoe part toward the die at the option of the operator.

6. In a perforating machine, a die holder, a die carried thereby, a hold-down detachably mounted with respect to said die and having two gripping elements constructed and arranged to retain a shoe part between said elements and to be reversed to locate it 110 either side up in a flat condition above the die, said elements having extending therethrough an opening similar in contour to the outline of the die, and means for positioning said hold-down and the gripped work upon 115 the die.

7. In a perforating machine, a die holder, a non-symmetrical die gang carried thereby, a hinge element located upon the die holder, and a hold-down comprising separable plates 125 normally supported as a unit above the die gang and having a hinge element constructed and arranged to cooperate with and to be separated from the hinge element upon the die holder, to allow pivotal movement of the 130

hold-down with respect to the die holder and removal therefrom.

8. In a perforating machine, a movable die holder, a die carried thereby, a hook-like hinge element located upon the die holder, a removable hold-down for gripping and supporting a shoe part in substantially flat condition above the die and having a cooperating detachable hinge element; and a spring for detachably holding said latter hinge element in the hook of the former element.

9. In a perforating machine, a die holder carrying a die, a spring actuated stripper plate associated therewith, a hold-down connected to the die holder and adapted to overlie the stripper plate and comprising members between which a shoe part may be interleaved and presented to the die as a unit with the hold-down above the stripper plate.

10. In a perforating machine, a die holder carrying a die, hook members secured to one end of the holder and constituting one element of a hinge, a hold-down comprising hinged plates with hinge pintles extended to fit in said hook members, and springs for detachably retaining said pintles in place in the hook members.

11. In a perforating machine, a die holder carrying a die, hinge members secured to the die holder, a hold-down comprising gripping plates having cooperating hinge members, said hinge members being so shaped as to be engageable and disengageable by relative longitudinal movement of the die holder and hold-down.

12. In a perforating machine, a die holder carrying a die, a hold-down comprising superposed holding plates hinged together and to the die holder, and means for accurately registering the hold-down with reference to the die.

13. In a perforating machine, a die holder carrying a die, a hold-down comprising normally separated hinged holding plates, means for separating said plates, means for connecting said plates to the rear end of the die holder, said plates being extended toward the front of the die holder to afford opportunity for the operator to press the holding plates together to hold a work piece and retain them in that condition during the operation of the machine.

14. In a perforating machine, a die, a removable and reversible hold-down comprising connected plates, one having gauges for a right shoe part and the other having gauges for a left shoe part, whereby a right or left shoe part may be located with reference to one plate or the other with its finished face uppermost, and means for positioning the hold-down with respect to the die as a unit with its contained shoe part.

15. In a perforating machine a non-symmetrical die, a hold-down therefor comprising superposed holding members with regis-

tering non-symmetrical openings therein similar to but larger than the contour of the die, and gauges effective on opposite faces of the hold-down for locating respectively reversely shaped shoe parts between the holding members.

16. In combination, a die, a removable hold-down mounted in predetermined relation thereto and comprising cooperating gripping members portions of which are substantially plane, said members being also provided with co-acting portions bent out of the planes of said other portions and constructed and arranged to hold a shoe part between them in bent condition even though said hold-down is removed, and gauge devices associated with the gripping members.

17. In a perforating machine, a die holder carrying a die, and a hold-down comprising gripping plates held in superposed relation and resilient means for separating said plates to permit insertion of the work, together with means for positioning said gripping plates with respect to the die.

In testimony whereof I have signed my name to this specification.
